CLAIM

The ornamental design for a snow accessory, as shown and described.

DESCRIPTION

FIG. 1 is a top right perspective view showing a second embodiment of the snow accessory;

FIG. 2 is a left side view thereof;

FIG. 3 is a right side view thereof;

FIG. 4 is a front view thereof;

FIG. 5 is a back view thereof;

FIG. 6 is a top plan view thereof; and,

FIG. 7 is a bottom plan view thereof.

The broken lines are for environmental purposes only and form no part of the claimed design.
